(57) **CLAIM**

I claim the ornamental design for an easy access wrap around padded cover with hook-and-loop fastener for laptop computer, as shown and described.

DESCRIPTION

FIG. 1 is a perspective view of an easy access wrap around padded cover with hook-and-loop fastener for laptop computer showing my new design partially closed, all other views showing my new design opened;

FIG. 2 is a top plan view thereof;

FIG. 3 is a bottom plan view thereof;

FIG. 4 is a side elevational view thereof, the elevational view of the opposing side being a mirror image thereof;

FIG. 5 is an end elevational view thereof; and,

FIG. 6 is an elevational view of the opposing end thereof.

1 Claim, 4 Drawing Sheets

FIG. 2

FIG. 4

FIG. 3

FIG. 5

FIG. 6
